UNITED STATES PATENT OFFICE.

GEORGE N. SIMPSON, OF CHICAGO, ILLINOIS.

CYLINDER-GRINDING MACHINE.

Application filed March 30, 1927. Serial No. 179,527.

This invention relates to improvements in cylinder grinding machines, and more especially to such a machine, device, or apparatus, for grinding the insides of relatively long cylinders or pipes. For example, in the making of long hydraulic or pneumatic lifting cylinders, it is necessary or desirable to smooth the inside surface of a relatively long casting or pipe to make the same true and smooth. By the use of my invention this operation can be efficiently and economically performed.

One of the features of my invention is the provision of means for supplying a substantially constant pressure on the abrasive wheel or grinding disk at all times. In devices as heretofore made the pressure on the grinding disk frequently varies with different positions of the disk in the cylinders causing considerable imperfections and unevenness in the work. In my improved apparatus the pressure on the grinding disk is substantially constant at all times. Another feature of my invention is the provision of means for adjusting the pressure on the grinding disk. In general, the grinding disk in my apparatus is supported at one end of a long housing, the driving shaft extending through said housing and being supported therein by two bearings at the ends. At one end, the shaft projects beyond the housing and carries the grinding disk, and at the other end the shaft projects and carries the driving mechanism. The housing is substantially entirely supported at one or more points between the driving mechanism and the grinding wheel, preferably at a point rather close to the driving mechanism; and the weight of the driving mechanism acts as a counterweight to balance to a certain extent the weight of the housing and shaft carrying the grinding disk. By adjusting the effective weight of the driving mechanism the pressure of the grinding disk on the work may be varied as desired. This feature will be shown and described more in detail herein-after.

In that form of device embodying the features of my invention shown in the accompanying drawings, Figs. 1 and 1^a together form a view in side elevation, a portion of the cylinder being shown in section to disclose the grinding disk inside, Fig. 2 is a view taken as indicated by the line 2 of Fig. 1^a, Fig. 3 is a view taken as indicated by line 3 of Fig. 1^a, Fig. 4 is a top plan view

of the grinding wheel drive assembly, Fig. 5 is a fragmentary view in top plan showing the reversing mechanism for changing the direction of rotation of the feed screw which moves the carriage carrying the grinding wheel driving mechanism, Fig. 6 is a view taken as indicated by the line 6 of Fig. 5, and Fig. 7 is a top plan view of the end of the grinding wheel shaft and housing therefor, showing the guard to maintain the driving wheel in proper position in the cylinder, and also showing the means for holding the grinder in proper position from the time the guard leaves the cylinder until it again reenters the cylinder.

Figure 8 is a sectional view taken on the line 8—8 of Fig. 7.

As shown in the drawings, the main supporting structure consists of two I-beams 10, 10 joined together by suitable channels 11, 11 resting on proper foundations 12, 12. At one end, the I-beams 10, 10 carry two transversely arranged I-beams 12^a, 12^a, which carry the main drive head consisting of a suitable clutch, chuck or cylinder holding device 13 on the end of an arbor or shaft 14 adapted to be driven through suitable gearing by a countershaft 15 carrying a suitable driving wheel or belt wheel 16 which may be rotated in any suitable manner. As here shown, the cylinder holding device 13 comprises a radial arm 17 having a foot 17^a to which the end of a cylinder 18 may be attached in any suitable manner and appropriately centered by placing blocks or shims 19 of requisite thickness. As here shown, the foot 17^a carries the plate 20 to the end of which the cylinder 18 is fastened by means of the U-bolts 21, 21. It will be seen that when the end of the cylinder or pipe 18 is suitably centered with respect to the shaft 14, that rotation of the wheel 16 will rotate the cylinder.

The other end of the cylinder is preferably rotatably supported on an auxiliary cylinder supporting structure comprising the two rollers 22, 22 rotatably mounted on suitable I-beams 23 transversely arranged and supported on the I-beams 10. The pipe is carried between and above these two rollers 22, 22 and is free to rotate thereon as the same is rotated by the main driving head.

I shall now describe the grinding wheel drive assembly. This includes a supporting frame or carriage 24 mounted on the four flanged wheels 25, 25 at the front and 25^a, 25^a at the rear, adapted for reciprocating motion

on the rails 26, 26 which, in turn, are mounted on suitable foundations 27, 27. Elevation of the carriage 24 is adjustable by means of the screws 27, 27 at the front, and 27^a, 27^a at the rear, as shown, in order to bring the grinding wheel shaft in proper position with respect to the particular cylinder to be ground. The rear end of the carriage 24 is not mounted directly on the rear wheels 25^a, 25^a but spiral springs 28, 28 are interposed between the wheels 25^a, 25^a and the rear end of the carriage. The adjusting screws 27^a, 27^a at the rear of the carriage permit the rear end of this carriage to be raised or lowered to place more or less weight on the wheels 25^a, 25^a through the springs 28, 28. In other words, the rear wheels 25^a, 25^a are arranged to take a certain proportion of the weight of the carriage 24 on the springs 28, 28; and the amount of weight thus taken is controlled by means of the screws 27, 27^a provided with shoulders engaging the tops of the springs. It will be seen that in this way the pressure of the grinding disk in the cylinder against the work may be adjusted. That is, lowering the rear end of the carriage 24 will cause the same to fulcrum on the wheels 25 to relieve the grinding disk from the work; and raising the rear end of the carriage will similarly cause the carriage to fulcrum on the wheels 25 to lower the grinding disk to increase its pressure against the work.

28, 28 indicates the grinding wheels arranged on the end of the grinding wheel shaft. Preferably, I use a long wheel of at least 8 to 10 inches in length, so as to grind the bumps and projections off the pipe and make the surface inside more nearly true. The fact that the grinding wheel stands a considerable length of pipe causes it to grind on projections and pass over depressions in the inside surface of the pipe. By the use of a long wheel, every time the wheel passes through the pipe, it will become more nearly smooth than the previous time and will become more nearly the same diameter since the portions of the pipe with a smaller diameter will be ground while portions of the pipe with a large diameter will not be ground. Instead of one solid long wheel I have here shown four separate wheels; but obviously the number of wheels, their length and the like is a matter of choice. Hereafter, in referring to the grinder or the grinding wheel, or wheels, it is to be understood that I mean the grinding apparatus carried at the end of the grinding wheel shaft, whether the same consists of one or more separate wheels. The grinding wheel 28 is carried on the end of a long shaft 29 supported in a long housing 30, a bearing as indicated by 31 being provided at the forward end and another bearing 32 at the rear end. The rear end of the shaft 29 is preferably directly connected to a driving mechanism, for example an elec-

tric motor 31^a mounted on the carriage 24. The rear end of the housing 30 is suitably supported on the carriage, preferably at a point or points substantially above the front wheels 25. As here shown, the rear end of the housing 30 is carried by the straps 35 fastened by means of the bolts 36 to the members 37 resting on the carriage 24. Preferably, the bearings in the housing 30 at each end are oil tight or fairly so. If desired, one or more additional bearings may be provided in the housing between the ends thereof. It will be seen that the weight of the rear end of the carriage 24 and the motor 31^a act as a sort of cantilever or counterweight to balance the forward end of the housing 30 and grinding wheel 28. In other words, the entire grinding wheel drive assembly can rock or fulcrum to a certain extent on the forward wheels 25, such motion being adjusted by means of the rear screws 27^a to raise or lower the rear end of the carriage to increase or lessen the downward pressure of the grinding wheel 28. It will be seen, however, that such pressure, no matter how adjusted, will be constant no matter what is the position of the carriage 24 on the rails 26.

In the grinding operation, the grinding wheel 28 is reciprocated back and forth through the pipe by means of the feed screw 33 driven by the shaft 34 through the reversing mechanism 35 (see Fig. 5). The shaft 34 may be driven in any suitable manner as by means of the chain 36 from the shaft 14. The reversing mechanism comprises two trains of gearing connecting the shaft 34 and the feed screw 33. One of these is a direct drive through the gears 38, 38 and the other is a reverse drive through the gears 39, 39 and intermediate reversing pinion 40. Two clutches 41 and 42 are provided, the former for engaging the direct drive and the other for the reverse. One or the other of these clutches is adapted to be engaged by means of the operating rod 43 carrying the two collars 44 and 45 near the forward and rear ends thereof. The carriage 24 carries arm 46 having a head 47 surrounding the rod 43 and adapted to engage the collars 44 and 45 at the forward and rear ends of its travel respectively, in order to throw in the reverse gear and forward gear respectively, to cause the feed screw 33 to reverse its rotation to cause the carriage 24 to travel back and forth on the rails 26.

One of the big problems in the type of cylinder grinding machine shown is to prevent vibration of the grinding wheel or stone as it performs its work. It has been found that if the stone lies at the bottom of the cylinder during the grinding, it has a tendency to run up one side or the other and fall back, thus causing chattering, vibrating or shaking. In order to prevent this vibration I provide a guard 50 attached to the end 130

of the housing 30 near its forward end. The guard 50 preferably has its end enlarged as indicated by 50^a, and is adapted to rest or bear against the side of the cylinder 18 in order to hold the grinding wheel 28 to one side of the bottom. In other words, the guard 50 is of sufficient length so that when it is in contact with the inside of the pipe, the wheel 28 is held over to one side of the pipe beyond the center line, far enough so that its tendency to run back to the bottom of the pipe and thus vibrate, is prevented. It has been found that the use of such a guard 50 with a proper adjustment prevents all tendency to vibrate.

It will be seen by reference to Fig. 7 that with the construction as shown, if the grinding wheel 28 is moved to the extreme end 18^a of the cylinder, the guard 50 will come out of the end of the cylinder. When thus out of the cylinder, there must be provided additional means to prevent chattering of the wheel 28 and to hold the wheel in proper position so when the carriage 24 starts forward again, the guard will enter the end of the cylinder. Such means comprise co-operating guide members 55 and 56, the former mounted on a suitable support 57 carried by the forward ends of the rails 26, and the latter comprising a strip welded or otherwise suitably attached to the forward end of the housing 30 on the same side as the guard 50. The strip 56 is preferably a rather long member; and the member 55 is similarly shaped and has its forward end preferably outwardly turned as indicated at 55^a. It will be seen (Fig. 7) that as the grinding wheel 28 nears the end of the cylinder, the guide 56 will engage the guide 55 to take the strain from the guard 50 and hold the wheel 28 in proper position. These guides 55 and 56 will remain in contact and perform this work from the time the guard 50 leaves the end of the cylinder until it again re-enters.

While I have shown and described certain embodiments of my invention, it is to be understood that it is capable of many modifications. Changes, therefore, in the construction and arrangement may be made without departing from the spirit and scope of the invention as disclosed in the accompanying claims, in which it is my intention to claim all novelty inherent in my invention as broadly as possible in view of the prior art.

What I claim as new, and desire to secure by Letters Patent, is:

1. In a cylinder grinding machine of the character described; means for supporting and rotating a cylinder; a grinding wheel shaft adapted to enter the cylinder; a housing for the grinding wheel shaft, said shaft projecting beyond the end of said housing and supported in a bearing carried by the end of the housing; a grinding wheel on the projecting forward end of the shaft; means

for rotating the grinding wheel shaft; means for reciprocating the grinding wheel longitudinally in the cylinder; and means for holding the grinding wheel away from the bottom of the cylinder, said means comprising a horizontally arranged guard arm having one end attached to the housing and the other end adapted to bear against the inside of the wall of the cylinder to prevent the grinding wheel from resting on the bottom of the cylinder.

2. In a cylinder grinding machine of the character described; means for supporting and rotating a cylinder; a grinding wheel shaft adapted to enter the cylinder; a housing for the grinding wheel shaft, said shaft projecting beyond the end of said housing and supported in a bearing carried by the end of the housing; a grinding wheel on the projecting forward end of the shaft; means for rotating the grinding wheel shaft; means for reciprocating the grinding wheel longitudinally in the cylinder; means for holding the grinding wheel away from the bottom of the cylinder and means to hold the grinding wheel in position from the time the same leaves the end of the cylinder until it again re-enters, said means including co-operating guide members, one being a stationary member beyond the end of the cylinder and the other a member on the housing, said guide members adapted to engage to hold the grinding wheel in position from the time the guard leaves the cylinder until it again re-enters.

3. In a cylinder grinding machine of the character described; means for supporting and rotating a cylinder; a grinding wheel shaft adapted to enter the cylinder; a housing for the grinding wheel shaft, said shaft projecting beyond the end of said housing and supported in a bearing carried by the end of the housing; a grinding wheel on the projecting forward end of the shaft; means for rotating the grinding wheel shaft; means for reciprocating the grinding wheel longitudinally in the cylinder; means for holding the grinding wheel away from the bottom of the cylinder, said means comprising a guard member attached to the housing and adapted to bear against the inside wall of the cylinder to prevent the grinding wheel from resting on the bottom of the cylinder; and means for holding the guard in position from the time the same leaves the end of the cylinder until it again re-enters, said means comprising co-operating guide members, one being stationary and mounted beyond the end of the cylinder and the other being carried on the housing, said guide members adapted to engage to hold the guard in position from the time it leaves the end of the cylinder until it again re-enters.

4. In a cylinder grinding machine of the character described; means for supporting and rotating a cylinder; a grinding wheel

shaft; a longitudinally reciprocable carriage supporting said shaft at one end; front and rear supports for said carriage; driving means for said shaft mounted on said carriage; a grinding wheel on the other end of said shaft adapted to enter the cylinder and be reciprocated longitudinally therein by said carriage; the driving means acting as a cantilever weight to balance the weight of the end of the shaft carrying the grinding wheel, the front supports of the carriage acting as a fulcrum; and means for varying the effective weight of the driving means to vary the grinding pressure of the grinding wheel.

5. In a cylinder grinding machine of the character described; means for supporting and rotating a cylinder; a grinding wheel shaft; a housing for said shaft; a longitudi-

nally reciprocable carriage supporting said housing at one end; front and rear supports for said carriage; driving means for said shaft mounted on said carriage; a grinding wheel on the other end of said shaft adapted to enter the cylinder and be reciprocated longitudinally therein by said carriage; the driving means acting as a cantilever weight to balance the weight of the end of the housing and shaft carrying the grinding wheel, the front support for the carriage acting as a fulcrum; and means for varying the effective weight of the driving means to vary the grinding pressure of the grinding wheel.

In witness whereof, I have hereunto set my hand this 24th day of March, 1927.

GEORGE N. SIMPSON.
